UNITED STATES PATENT OFFICE.

WILSON E. SYMONS, OF CHICAGO, ILLINOIS.

CAR STRUCTURE.

No. 866,403.

Specification of Letters Patent.

Patented Sept. 17, 1907.

Application filed March 30, 1907. Serial No. 365,484.

To all whom it may concern:

Be it known that I, WILSON E. SYMONS, a citizen of the United States, residing at Chicago, in the county of Cook and State of Illinois, have invented a new and 5 useful Car Structure, of which the following is a specification.

This invention relates to car structures, and more particularly to the underframing for car bodies.

One of the principal objects of the present invention 10 is to provide an end sill composed wholly or partially of metal, said sill being strong, and practically indestructible, in order that it will withstand the rough usage and hard strains incident to this type of structure, and furthermore having effective means, whereby the 15 longitudinal sills and the car siding can be secured in place.

In the accompanying drawings:—Figure 1 is a plan view of one embodiment of the invention. Fig. 2 is an end view of the same. Fig. 3 is a cross sectional view. 20 Fig. 4 is a side elevation of one of the joints between the sill sections. Fig. 5 is a detail perspective view of one of the clamping plates. Fig. 6 is a cross-sectional view through the structure shown in Fig. 4. Fig. 7 is a detail horizontal sectional view through one of the 25 plates, showing the particular construction of the spurs. Fig. 8 is a detail perspective view of a slightly modified form of construction. Fig. 9 is a detail view of another modification.

Similar reference numerals designate corresponding 30 parts in all the figures of the drawings.

In the embodiment illustrated, the end sill of the car comprises a metallic shell preferably, though not necessarily composed of cast steel and having an upper wall 10, a lower wall 11, and a rear wall 12 that connects 35 said upper and lower walls. The rear wall is provided with sets of spaced rearwardly extending ears 13, and between these ears, mortises 14 are formed in said rear wall. The front side of the shell is open, but the upper and lower walls 10 and 11 are preferably provided with 40 oppositely disposed inwardly extending flanges 15 that terminate short of each other. Other inwardly extending flanges 16 are carried by intermediate portions of the upper and lower walls 10 and 11, and constitute stops, as hereinafter explained.

45 The end sill can be employed under certain conditions, as thus constructed, but there is preferably located therein, a wooden core 17, which fits snugly between the upper and lower walls 10 and 11 and the flanges 15 and 16. This core has on its outer side a 50 longitudinal rib 18 that extends between the flanges 15, and projects from the open side of the shell. In practice, the core may preferably be composed of two or more sections driven through opposite ends of the

shell. As shown in Fig. 3, the rib 18 constitutes convenient means to which the siding 19 can be nailed, 55 as shown at 20. Moreover, it will be evident that this rib projecting beyond the outer face of the shell, serves to space the siding therefrom.

The longitudinal sills, designated 21, have their ends fitted between the ears 13 of the different sets, to 60 which ears, they are secured by transverse bolts 22. The said ends of the longitudinal sills are furthermore provided with tenons 23, which tenons engage in the mortises 14, and project into the shell, as illustrated in Fig. 3. It will be observed, however, that said 65 tenons terminate short of the vertical plane of the flanges 16, and inasmuch as the rear side of the core 17 is abutted against the outer sides of said flanges, the tenons are spaced from the core. The longitudinal sills 21 are each preferably constructed of two or more 70 sections, these sections being arranged end to end, and having a broken joint 24 between them. In order to effectively secure the sections together without weakening the sills by a plurality of comparatively large vertical bolt openings therethrough, the following mechanism is preferably employed. Clamping plates 25 are located on opposite sides of the sections 75 and bridge the joints between them. These plates are provided on their sides with inwardly projecting spurs 26, which spurs are pointed, and have certain 80 of their sides, as 27 perpendicular to the inner face of the plate, while the opposite sides are arranged at an inclination, as shown at 28. The spurs that engage in one of the sections have their corresponding faces disposed in perpendicular relation, as described, while 85 those that engage in the other sill section have their opposite faces perpendicular. This it will be thought will be clear by reference to Fig. 7. The spurs are embedded in the sections, and the plates are held in position by transverse horizontal bolts 29 that pass through 90 said plates and through the sections. Preferably a single and comparatively small vertical bolt 30 extends through the overlapping ends of the sections.

In one embodiment of the invention, the clamping plates are provided along their lower edges with longitudinal flanges 31, which extend beneath the sills. 95 These flanges are preferably provided with depending eyes 32, to which the brake rigging or portions thereof may be secured if desired. The flanges 31 are not entirely essential, and may be dispensed with, as illustrated in Fig. 8, wherein a plate 33 is disclosed having the usual spurs 34. Plates of the character shown in Fig. 8 are particularly useful where the joints between the sill sections are located over the transoms or needle beams of the truck. These plates are preferably of 100 cast steel, though they may be of iron or wrought

metal, in fact they may be made of heavy sheet material, in which case, as illustrated in Fig. 9, the plate 35 has its spurs 36 struck directly from the metal. While in Fig. 1, the joints between the sections of the 5 longitudinal sills are shown substantially side by side, because of the cutting away of the said sills, it will be evident to those skilled in the art, that in practice these joints or splices are disposed in staggered relation in order to preserve the strength of the under frame as a 10 whole.

An under-frame for car bodies is thus constructed, that is very strong and durable, the metal is practically indestructible, and while wood may and is preferably employed as a core, this wood need not be of the high 15 and expensive grade that is necessary for the ordinary end sill. Moreover, it will be evident that the ordinary siding and longitudinal sills may be effectively secured to the end sills. While the longitudinal sills are shown of wood, and can be made of comparatively short 20 sections, still it will be observed to those skilled in the art, that metallic longitudinal sills may be employed in connection with the end sill set forth.

From the foregoing, it is thought that the construction, operation, and many advantages of the herein 25 described invention will be apparent to those skilled in the art, without further description, and it will be understood that various changes in the size, shape, proportion, and minor details of construction, may be resorted to without departing from the spirit or sacrificing any of the advantages of the invention. 30

Having thus fully described my invention, what I claim as new, and desire to secure by Letters Patent, is:—

1. An end sill for cars comprising a metallic shell having an open side, and retaining means for a core carried by the marginal portion of the open side of said end sill. 35
2. An end sill for cars comprising a metallic shell having an open side, and an inwardly extending flange located along the margin of the shell and extending partially across the open side thereof. 40
3. An end sill for cars comprising a metallic shell having an open side, oppositely disposed inwardly extending flanges located along the margins and extending toward each other across the open side, but terminating short of each other. 45
4. An end sill for cars comprising a metallic shell composed of upper and lower walls, a rear wall having means for engagement with the longitudinal sills, and flanges carried by the front margins of the upper and lower walls, 50 said flanges extending toward each other.
5. An end sill for cars comprising a metallic shell having an open front side and a flange extending partially across the open side, and a wooden carrier located in the shell and maintained against lateral outward movement 55 by the flange.
6. An end sill for cars comprising a metallic shell having a top, a bottom and an open front side, and flanges extending from said top and bottom partially across the open side, and a wooden carrier located in the shell and 60 maintained against lateral outward displacement by said flanges.
7. An end sill for cars comprising a metallic shell having an open front side, and flanges extending partially across the open side, and a wooden core located in the shell and having a longitudinally disposed rib located 65 between the flanges.
8. An end sill for cars comprising a metallic shell composed of upper and lower walls, a rear wall having means for engagement with the longitudinal sills, flanges carried

by the front margins of the upper and lower walls, said 70 flanges extending toward each other, and a wooden core located in the shell between the upper and lower walls and having a longitudinal rib located between the flanges and projecting from the open side of the shell.

9. An end sill for cars, comprising a metallic shell composed of upper and lower walls having front portions spaced apart, leaving an open side, longitudinal flanges carried by intermediate portions of the inner sides of the walls, forming stops, and a core located in the shell and having its rear side disposed against the flanges and its 80 front side exposed through the open side of the shell.

10. An end sill for cars comprising a shell having means at its rear side for engagement with the longitudinal sills, of a core located in the shell, and means arranged within the shell for spacing the core from the ends of the longitudinal sills. 85

11. An end sill for cars comprising a metallic shell having a rear wall provided with tenon-receiving mortises, a core located in the shell, and means arranged within the shell for spacing the core from the ends of the tenons 90 placed in the mortises.

12. An end sill for cars comprising a metallic shell having an inner or rear wall provided with sets of spaced rearwardly extending sill-engaging ears, and a mortise or opening located in said inner or rear wall between the 95 ears of each set.

13. An end sill for cars comprising a metallic shell composed of upper and lower walls, a rear wall provided with sets of spaced rearwardly extending sill-embracing ears and mortises located between the ears, and inwardly extending flanges carried by the outer margins of the upper and lower walls and terminating short of each other, a core located in the shell and having a rib projecting between the flanges, and stop flanges carried by the upper and lower walls and engaging the rear side of the core. 100

14. In a structure of the character set forth, the combination with a metallic end sill, of longitudinal sills, means for securing the longitudinal sills to the end sills, said longitudinal sills comprising sections, and means for securing the sections together, said means comprising 110 section-embracing plates located on opposite sides of the sections and having oppositely extending spurs that are embedded in the outer sides of the sections, and means for clamping the plates together.

15. In a structure of the character set forth, the combination with a metallic end sill, of longitudinal sills, means for securing the longitudinal sills to the end sills, said longitudinal sills comprising sections, means for securing the sections together, said means comprising section-embracing plates located on opposite sides of the sill 120 sections and having oppositely extending spurs that are embedded in the opposite outer sides of said sections, and bolts passing through the plates and sections.

16. In a structure of the character set forth, the combination with sill sections, of clamping plates located on 125 opposite sides of the sill sections and bridging the joints between the sections, said plates having oppositely extending spurs embedded in the opposite outer sides of said sections, and means for securing the clamp plates together.

17. In a structure of the character set forth, the combination with sill sections, of flat clamping plates bridging the joints between the sections and located against the opposite sides thereof, said plates having spurs embedded in the opposite sides of said sections, and bolts 135 passing through the sections and plates for securing the same together and maintaining the spurs embedded in the sections.

18. In a structure of the character set forth, the combination with sill sections, of clamping plates bridging 140 the joints between the sections and located on opposite sides of spaced sections, said plates having oppositely extending spurs that are embedded in the opposite sides of the sections and having flanges extending along the under sides of said sections, and means for securing the clamping plates together. 145

19. In a structure of the character set forth, the combination with sill sections disposed end to end and having a broken joint, of clamping plates located on opposite sides of the sill sections and bridging the joint, said plates having spurs projecting from their inner sides and embedded in the sill sections, the spurs that engage in one section being beveled in an oposite direction to those that engage in the other, and bolts passing through the plates and the sill sections for securing the same together.

In testimony, that I claim the foregoing as my own, I 10 have hereto affixed my signature in the presence of two witnesses.

WILSON E. SYMONS.
